HOMOGENIZING MACHINE

Reinhard A. Yohpe, Battle Creek, Mich., assignor to Union Pump Company, Battle Creek, Mich., a corporation of Michigan

Filed Nov. 21, 1960, Ser. No. 62,906

Term of patent 14 years

(Cl. D23—1)

Fig. 1

FIGURE 1 is a perspective view of a homogenizing machine embodying my new design, showing a portion of the top, the front, and one side thereof, the front being at the right.

FIGURE 3 is a perspective view thereof, showing a portion of the top, the front, and the other side of the homogenizing machine.

I claim:

The ornamental design for a homogenizing machine, substantially as shown.
